[57] CLAIM

The ornamental design for a low drag vehicle rear view
mirror, as shown and described.

DESCRIPTION

FIG. 1 is a perspective view of my low drag vehicle
rear view mirror showing my new design;
FIG. 2 is a front elevation view thereof;
FIG. 3 is a rear elevation view thereof; and
FIG. 4 is an end elevation view thereof; and
FIG. 5 is a top plan view thereof, the bottom being a
mirror image of that shown.
